UNITED STATES PATENT OFFICE.

JOHN EDWARD GOODWIN, OF STOKE-UPON-TRENT, ENGLAND, ASSIGNOR TO JOSIAH WEDGWOOD & SONS LTD., OF ETRURIA, ENGLAND, A CORPORATION OF GREAT BRITAIN.

DESIGN FOR A PLATE OR SIMILAR ARTICLE.

43,843.

Specification for Design.

Patented Apr. 15, 1913.

Application filed January 15, 1913. Serial No. 742,284. Term of patent 7 years.

To all whom it may concern:

Be it known that I, JOHN EDWARD GOODWIN, a subject of the King of England, residing at Stoke-upon-Trent, in the county of Stafford, in England, have invented a new, original, and ornamental Design for a Plate or Similar Article, of which the following is a specification, reference being had to the accompanying drawing, forming part thereof.

The figure is a plan view of a plate showing my new design.

I claim:

The ornamental design for a plate or similar article, as shown.

JOHN EDWARD GOODWIN.

Witnesses:

HENRY ROBERT KING,
WILLIAM MAYER.
